UNITED STATES PATENT OFFICE.

FINLY F. JOSEPH, OF CHICAGO, ILLINOIS.

COAL-HANDLING APPARATUS.

1,086,536.

Specification of Letters Patent. Patented Feb. 10, 1914.

Application filed January 6, 1913. Serial No. 740,271.

To all whom it may concern:

Be it known that I, FINLY F. JOSEPH, a citizen of the United States, residing at Chicago, in the State of Illinois, have invented certain new and useful Improvements in Coal-Handling Apparatus, of which the following is a specification.

My invention relates to elevators for loose material, such as broken coal, and its primary object is to render more efficient the apparatus for handling freight in transfer buckets, as for instance in carrying from a receiving hopper to an elevated receptacle.

I have illustrated the invention in a preferred form in the accompanying drawings in which—

Figure 1 is a diagrammatic view and partial section, showing the arrangement of the bucket carrier with relation to a coal chute. Fig. 2 is a partial side elevation of the bucket and supports looking to the right, near the top of Fig. 1. Fig. 3 is a top plan view of the outer trolley end of the carrier and guideway. Fig. 4 is a section showing the bucket and gate in position at the mouth of the coal chute, the section being on the line (IV)—(IV) in Fig. 5, while Fig. 5 is a vertical section at right angles to that of Fig. 4, along the line (V)—(V) in Fig. 4, showing the supports for the gate of the coal chute. Fig. 6 is a plan view of the bucket and gate in the position shown in Fig. 4.

Cylindrical gates for controlling the discharge from a receiving hopper have been used heretofore, but they have either been arranged to act as a double gate, or have been used in connection with a second gate, with the result that the coal bucket must be landed at a position below the mouth of the chute, while the loading has been dependent upon extra measuring devices. In my device I use the coal bucket itself as the second gate and arrange for finally dumping the charge of coal to the bottom of the bucket only after the full charge has been received.

While the use of cables and guideways for the buckets is old in general, there have been disadvantages in the swinging of the bucket and in the passage of the same around curves in the guideways. I employ a trolley support for the cable, which being equipped with the socket supports for the bucket moves with the bucket itself at the proper time and renders the action more certain,

prevents idle swinging of the bucket, and secures other advantages to appear hereafter.

As shown in the accompanying drawings, I provide near the mouth 7 of the hopper, an inclined landing platform 8 which may or may not be provided with a counterweighted truck 9 thereon, and which is used to receive the coal bucket 10 and place it ready for filling. That is, the bucket in descending lands upon the truck 9 and then moves back against the abutment 7^a directly under the end of the coal chute 7, avoiding any spill of material. As shown more clearly in Figs. 4 and 5, it takes position under the cylindrical gate 11, 13, and inclosing part of it, the bucket sides entering between the trunnion supports 12^a, 12^a, of the gate and the gate itself. The short shafts 12 have loosely mounted upon them, these supporting arms 12^a which carry the gate closing the chute 7. This cylindrical gate has a depending skirt 13 which normally extends to a point about flush with the bottom of the chute as shown in Figs. 1 and 4, but it is of size to extend within the bucket 10 as shown in dotted lines in Fig. 4, in the act of opening, the supporting arms remaining outside the bucket as shown in Fig. 5.

The cylindrical wall of the gate 11 has an opening 14 normally above the position of the coal in the chute; and it will be observed that when the gate is revolved downward so that the skirt 13 extends into the bucket as shown in Fig. 4, the opening 14 will register with the chute and allow the coal to flow in until the top part of the bucket is filled, the charge being held in suspended position by the skirt 13. The coal chute is then closed by the rising of the gate with its skirt 13, which, by withdrawing from the bucket, simultaneously dumps a charge in the bottom thereof.

Arranged near the landing platform 8, I provide guideways 15 which engage rollers 16 on the sides of the bucket, while at another point on each side of the bucket I attach a hoisting cable 17, running over the idle sheave 18 and thence over the main sheave 19, which is on a trolley 20, whose carrying wheels 21 and 22 rest in a hooked extension 23 of a guide-track 24 placed near the elevated position at which the freight is to be delivered. The hoisting cable 17 attached to the bucket, passes from the sheave 19 to movable sheave 25 having

horizontal travel in guideways 26, and thence over any other convenient sheaves, as 27, to the hoisting engine. In operation, the bucket is hoisted between the pair of sheaves 18 and guided by the guideway 15, until the pins 28 on the bucket strike the forked arms 29 of the trolley 20, whereupon the trolley will be carried along with the cable and bucket, the wheels 21 and 23 riding in the track 24. At the proper point I place a tripping bar 30 which engages the tailend of the spring or counterweight catch 31, which retains the dumping gate 32 of the bucket 10, as will be evident.

15 It will be observed that the terminal sheaves 25 for the hoisting cable 17, instead of being stationary are allowed to travel horizontally on the guideways 26, against the tension of a counterweight 33 and an auxiliary cable 34, so that the travel of these sheaves relieves shock on the cable and also takes up all slack of the cable at all times. This cable 34 is supported at this point on pulleys 35 and 36 and continues over pulleys 37 and 38 and is attached to the gate 11 by pin 39 and thence proceeds over pulleys 40, 41 and 42 back to the movable block 25^a supporting the main cable sheave 25. As soon as a pull is exerted on the loaded bucket 11 therefore, tension is exerted on the cable 34 by movement of block 25^a, so that the pin 39 on the gate is pulled upward and the gate is closed. On the other hand when the tension on the cable 17 is relieved by the landing of the bucket against the wall 7^a, the counterweight 33 will pull on the cable 34 by block 25^a, and this will throw down the closing gate 11 into the bucket, causing the opening 14 therein to register with the coal chute, admitting the charge to load the bucket.

It will be observed that by the above described mechanism, the operation is automatic, depending on the handling of the hoisting engine alone. When the empty bucket descends it lands in place directly at the mouth of the chute and by the act of landing causes a slack in the cable 34, allowing a movement which causes the gate to open and extend into the bucket, while the bucket meantime acts as a stop gate upon receiving the charge. Upon exerting tension on the hoisting cable, the action is to close the gate by lifting the depending skirt out of the bucket, which thereupon deposits the load on the bottom of the bucket. When the loaded bucket arrives at the lower stationary position of the trolley 20, the bucket itself carries the trolley, by pin 28, which, together with the guide 15, gives a firm and accurate support for the weight of the bucket as soon as it passes out of the direct vertical support of the hoisting cable. It is of course understood that the trolley track 24 extends to whatever position it is desired

to dump the load. The use of this trolley together with the guide 15 prevents any swinging of the bucket either when loaded or empty and the use of the counterweight 33 allows for taking up any overwind without disturbing the relation of the parts. 70

I regard the use of the perforated gate with a skirt extending into the bucket during the loading, and the use of a movable head shaft and sheaves, and the use of the traveling trolley, and the use of an inclined landing platform, as important parts of my invention. 75

The various advantages of the apparatus will readily occur to those familiar with the art. 80

Having thus described my invention and illustrated its use, what I claim is the following:

1. Coal handling apparatus comprising a bucket, a guideway for the bucket having a vertical portion, an elevated trolley track and a trolley thereon, said guideway and trolley track having substantially parallel approximately horizontal portions, a hoisting cable passing over said trolley and normally in line with the guideway in the act of vertical hoisting and adapted to be moved along the trolley upon contact with the load on the cable, substantially as described. 95

2. In coal handling apparatus the combination of a delivery hopper and pivoted gates therefor, a traveling hoisting bucket, a cable therefor having an end attached to a movable counterweighted support, an auxiliary cable operating the said gate and controlled by said movable support, whereby the tension on the hoisting cable effects the opening and closing of the delivery gate, substantially as described. 100

3. In freight handling apparatus, the combination with a carrying bucket and a delivery chute, of a gate for the said chute adapted to revolve into and out of position to stop the chute, and provided with an opening therein through which to deliver the material, when the gate drops into the bucket, said gate having a depending skirt on the bucket retaining the material until the charge is completed, substantially as described. 115

4. Coal handling apparatus comprising a delivery chute and a hoisting bucket, and a movable landing platform having means to carry the bucket directly under the chute, the chute being provided with a single gate adapted to enter and deliver directly into the bucket a measured charge. 120

5. In coal handling apparatus, the combination with a delivery chute, a landing platform, a bucket and a hoisting cable, a mounting for said hoisting cable including a traveling counter-weighted sheave and devices connected to said traveling sheave to operate the delivery gate by the applica- 125

- tion and release of tension on the hoisting cable.
6. The combination with a freight bucket and a hoisting cable therefor, of vertical and horizontal rigid guides for the bucket to prevent its swinging, and devices to move the supporting means for the hoisting cable along with a bucket on part of its travel in changing from vertical to horizontal, substantially as described.
7. In coal handling apparatus, a delivery gate comprising a pair of steady trunnions, supporting arms loosely mounted on the trunnions, a cylindrical gate attached to the outer end of the arm and adapted to extend within the coal carrying bucket so as to prevent the immediate tripping of the
- material at the bottom of the bucket, substantially as described.
8. In coal handling apparatus, the combination with a carrying bucket and a delivery chute, of a cylindrical gate stopping the chute and provided in its cylindrical face with an opening through which to deliver the material while a part of the gate supports the material on its backside within the bucket, substantially as described.
- In testimony whereof I have hereunto signed my name in the presence of the two subscribed witnesses.

FINLY F. JOSEPH.
